BATTERY BOX OR CONTAINER

Raleigh E. Tresise, Cleveland Heights, and Paul D. Kendall, Maple Heights, Ohio, assignors to Paraphone Hearing Aid, Inc., Cleveland, Ohio, a corporation of Ohio

Application August 16, 1941, Serial No. 407,182

5 Claims. (Cl. 136—173)

This invention relates to containers for batteries and more particularly to containers for batteries generating current for use with the amplifiers for small vacuum tubes, such as are used in hearing aids and in small radio sets.

One of the general purposes and objects of the invention is the production of a container for this purpose which, when used in connection with hearing aids of the vacuum tube type, will be compact and light in weight, thereby enabling the same to be worn with comfort by the users of such hearing aids.

Further objects of the invention are to provide battery containers with improved means for mounting and supporting the batteries therein; also to provide containers of the character referred to with simple and efficient means for preventing the accidental short-circuiting between the prongs of the plugs which are insertable within the sockets with which the containers are provided.

We accomplish the foregoing objects in and through the construction and arrangement of parts shown in the drawing hereof, wherein Fig. 1 represents a side elevation of a battery box or container constructed in accordance with our invention, parts therein being shown in dotted lines; Fig. 2 a sectional view corresponding to the line 2—2 of Fig. 1; Fig. 3 a sectional view corresponding substantially to the line 3—3 of Fig. 2, the A battery being shown in elevation after "2"; Fig. 4 a bottom plan view, and Fig. 5 a top plan view of the container shown in the preceding views; Fig. 6 a detail in section corresponding to the line 6—6 of Fig. 2; and Fig. 7 a detail in section corresponding to the line 7—7 of Fig. 2 and looking in the direction of the arrows.

Describing by reference characters the various parts shown in the drawing, 10 denotes the front or cover section and 11 the rear or back section of our battery box or container. These sections are identical in shape and dimensions and each of the same is provided with side walls and top and bottom walls, the top and bottom walls of the front or cover section being indicated at 10^a and 10^b respectively and the side walls of the same being indicated at 10^c, while the top and bottom walls of the rear section 11 are indicated respectively at 11^a and 11^b and the side flanges at 11^c. The sections of the box or container are made of light sheet metal, pressed to shape and are provided each with vertically spaced ribs extending transversely therearound from one side edge to the opposite side edge, the ribs of section 10 being indicated at 10^d and those on section

11 being indicated at 11^d. The meeting edges 10^e and 11^e of the sections are provided each with a short outwardly projecting flange, said flanges constituting jointly an outwardly directed rib, 5 from which rib the ribs 10^d and 11^d extend in opposite directions. In practice, the front and rear sections of the containers are enameled, and these transversely extending ribs not only strengthen the light metal of which the container is formed, 10 but also serve to support the containers upon any surfaces upon which they may be placed without injury to the enameled coating of the bodies thereof.

As shown herein, the rear section of our battery box container is provided with means for mounting therein an A-battery and a B-battery, with suitable electrical connections between the said batteries, the container, and the socket contacts for the prongs of the plug by which the current is conducted to a vacuum tube amplifier (not shown). The batteries referred to are designated respectively A and B and are mounted in the rear section in the following manner: 12 denotes a block of insulating material constituting 15 the base of a socket and having a contact 13 at its lower end for engagement with the positive pole 13^x of the A battery, the said contact having a hollow stem or sleeve 13^a extending upwardly into the block 12 for the reception of one of the 20 prongs of the plug whereby current is supplied from the A battery to one end of the filament circuit of the vacuum tube amplifier. The battery is supported between the contact 13 and the bottom wall 11^b by means of a contact arm 14 25 having an upper rounded end 14^a adapted to engage the bottom of the battery and having its lower end 14^b mounted for rotation upon a shaft 15 which is supported between the lugs formed by the upturned flanges 16^a of an inverted U-shaped base electrically connected to the flange 11^b as by rivets 16^b. A torsion spring 17 is wound 30 around the shaft 15 and has one end connected to the arm 14^a, its other end being provided with a projection 17^a extending through an opening in 35 the adjacent flange 16^a.

The upper end or positive pole of the B-battery engages a contact 18 carried by an insulating block 19, secured to the upper wall 11^a of the rear container section by rivets 19^b while the lower end is engaged by a contact arm 20, similar 40 to the arm 14 and mounted in a similar manner upon a shaft 21 mounted in the lugs formed by the upturned flanges 22^a of an inverted U-shaped base 22, which is electrically connected with the 45 casing section, as by means of rivets 23. A spring 50

24, similar to spring 17, is mounted on the shaft 21 and has one end secured to the arm 20 and its opposite end provided with a projection 24^a extending through an opening in the adjacent flange 22^a. The block 12 of insulating material not only serves to space the contact 13 at the proper distance from the contact arm 14, but also serves to prevent a short circuiting between the terminals of the A and B batteries, as by the insertion of a knife for the removal of the plug, which would result in tube failure.

As the bottoms, or exposed portions of the bottoms, of dry cells usually constitute the negative poles of the same, the contact arms 14 and 20 and the mode of operating the same are particularly efficient in obtaining and maintaining clean contact between the upper ends of these arms and the exposed bottom portions of the battery casings, since the action of the springs 17 and 24 produces a wiping of the upper ends of the arms against the portions of the bottoms of their respective casings engaged by said ends as the batteries are assuming their final positions within the container. The fact that the contacts are located in the rear section enables the A and B batteries to be very conveniently introduced into said section by first engaging the bottom negative poles of the same with the upper ends of their respective contact arms 14 and 20. Then, by pressing the batteries downwardly upon these contact arms, the positive poles of the batteries may be brought below their respective contacts, after which the tops of the batteries may be swung inwardly and the lower contact arms will hold them firmly in the positions in which they have been thus placed, with the positive poles in engagement with the upper contacts. During this operation, the upper ends of the arms 14 and 20 exercise their wiping action against the bottom portions or negative poles of their respective batteries.

A conductor 25 extends from the contact 18 to and is connected with the lower end of a hollow stem or sleeve 13^b adapted to receive another one of the prongs of the plug by which current is supplied to one side of the plate circuit of the vacuum tube amplifier. 26 and 26^a denote posts carried by the wall 11^a, on opposite sides of the semi-circular opening 27 therein, which posts support one or more fiber disks 28, constituting the socket from which the insulating block 12 is in turn supported by the screw 29. This socket has openings for the reception of the prongs of the plug, which openings register with the sleeves 13^a and 13^b and with a third sleeve 13^c. The socket is spaced from the wall 11^a by means to be described. The container with which the lower ends of the batteries A and B are electrically connected is in turn electrically connected by a conductor 30 with the sleeve 13^c which registers with a third opening in the socket, provided for the reception of the third prong of the plug, whereby the return circuit for the A and B batteries from the filament and plate of the vacuum tube is completed through said sleeve, prong, and container.

31 denotes a thin forwardly curved strap-like guard which is sleeved at one end around the post 26 and at its opposite end around the post 26^a located beneath a narrow plate 32 extending beneath the top flange 11^a and having a down-turned end 32^a secured, as by riveting, to the interior of the rear wall 11. The sleeves by which the guard is secured to the posts 26 and 26^a constitute means for spacing the socket 28

and the insulating block 12 attached thereto from the walls 10^a and 11^a of the container. This guard prevents the accidental engagement of the top wall of the front or cover section with

5 the prongs inserted into the sleeves 13^a and 13^b, while securing the said sections together, or while disconnecting the said sections, which accidental engagement would cause the momentary transmission of the high voltage B current into the filament circuit thereby burning out the filament.

The plate 32 is provided with a pin 33 projecting upwardly therefrom, said pin being adapted to project through an opening 34 in the 15 top wall 10^a of the front or cover section of the receptacle. A similar pin 36 projects downwardly from the outer end of a spring plate 35 which has an upturned end 35^a which is secured against the wall 11^a, as by means of rivets 35^b, of the 20 rear or bottom section of the container. This pin is adapted to enter an opening 37 provided for its reception in the bottom wall 10^b of the cover section. For the purpose of removing the pin from the opening 37, the spring plate has attached thereto a stud 38 having a push button 38^a at the lower end thereof, said stud extending through an opening provided in the bottom wall 11^b of the rear or bottom section of the box. The construction by which the front and rear sections 30 of the container are connected enables us to obtain a stronger box, with the use of the same weight of metal, than can be obtained where one or more hinges are employed as a means for connecting the sections, since we eliminate the extra metal in these sections that is requisite to enable them to embody this hinged construction.

For convenience of description, the battery box or container is assumed to be in the position shown in Figs. 1, 2 and 3 of the drawing, and the terms "top," "bottom" and "sides" have been applied to the walls of the box or container in conformity with this assumption. However, it will be understood that these terms are merely descriptive and are not intended to limit the positions in which the container and its contents may be placed.

Having thus described our invention, what we claim is:

50 1. A metallic battery box container comprising a rear section and a front or cover section, the rear section having a back wall and top and bottom walls, a contact insulated from and supported adjacent to the top wall, a socket spaced laterally from said contact and comprising a block of insulating material extending downwardly from below the top wall and provided with a contact at its lower end having a hollow stem extending upwardly into said block for the reception of a prong of a plug, a pair of laterally spaced contacts vertically opposed to the former contacts and grounded to the rear section, each vertically opposed pair of contacts adapted to receive a dry battery therebetween with the opposite poles of the battery in engagement with the vertically opposed contacts of such pair, the said socket also having an additional hollow contact stem for the reception of an additional prong of said plug, and means for electrically connecting the first mentioned contact with the second mentioned hollow stem.

70 2. In the battery box set forth in claim 1, each of the second pair of contacts comprising an upwardly extending arm pivotally supported by the rear section and spring means for urging the

upper portion of the same into engagement with the pole of the battery thereabove.

3. A metallic battery box or container comprising a rear section and a front or cover section, each section having top, bottom and side walls, the said sections being adapted to be secured together to form a closed compartment, the top wall of one of the said sections being provided with an opening for the reception of a plug and with a socket below said opening and itself having openings for the reception of the prongs of said plug, there being contacts located below the socket openings, batteries in said container having their poles electrically connected with the said contacts respectively, a strap-like curved guard, and means for supporting the opposite ends of said guard, said means being located on the wall having the opening for the socket and on opposite sides of the opening and supporting said ends below the said wall, the said guard projecting outwardly beyond the openings in said socket and beyond the top wall of the section having the socket and adapted to be received beneath the top wall of the other section when the said sections are united.

4. A metallic battery box or container comprising a rear section and a front section, each section having top, bottom and side walls, the said sections being adapted to be secured together to form a closed compartment, the top walls of the said sections being provided each with a sectional opening adapted, when the sections are united, to provide jointly a complete opening for the reception of a plug having a plurality of prongs, a socket located below and spaced from the opening in the top wall of one of said sections and itself having openings for the reception of said prongs, the said socket extending beyond the opening in the top wall of the last mentioned section and adapted to extend at least partially across the opening in the top wall of the other of said sections when the said sections are connected, there being contacts located below the openings in said socket and there being batteries in said container having their poles electrically connected with the said contacts respectively, a strap-like curved guard, and means for

supporting the opposite ends of said guard, said means being located on opposite sides of the opening in the wall having the socket and supporting said ends below the said wall, the said guard projecting outwardly beyond the openings in said socket and beyond the top wall of the section having the socket and adapted to be received beneath the top wall of the other section when the said sections are united.

5. A metallic battery box or container comprising a rear section and a front or cover section, each section having top, bottom and side walls, the said sections being adapted to be secured together to form a closed compartment, the top walls of the said sections being provided each with a semi-circular opening adapted, when the sections are assembled, to form a circular opening for the reception of a plug, means for supporting A and B batteries within the said rear section and between the top and bottom walls thereof, with the negative poles of the said batteries electrically connected with the metal of said section and with the positive poles in engagement with contacts adjacent to and insulated from the upper wall of said section, a socket of insulating material located below the circular opening provided beneath the top walls of the container sections and supported by the top wall of the rear sections, the said socket having a plurality of openings therethrough, contacts located below the said openings and adapted to be engaged by the prongs of a plug inserted thereinto, means electrically connecting the last mentioned contacts with the insulated contacts and with the metal of the rear section respectively, a forwardly strap-like curved guard supported beneath the top wall of the rear section and adapted to project below the top wall of the front section when the said sections are assembled, the openings in said socket being located below the semicircular opening of the rear section and the said guard being supported between the top wall of the rear section and the said socket.
